UNITED STATES PATENT OFFICE.

HERMAN A. SAFION AND MORIS GERINGER, OF NEW YORK, N. Y.

DESIGN FOR A LIGHTING-FIXTURE ARM.

61,417.

Specification for Design. Patented Aug. 29, 1922.

Application filed January 27, 1922. Serial No. 400. Term of patent 3½ years.

To all whom it may concern:

Be it known that we, HERMAN A. SAFION and MORIS GERINGER, citizens of the United States, residing at New York, in the counties of New York and Kings, respectively, and State of New York, have invented a new, original, and ornamental Design for a Lighting-Fixture Arm, of which the following is a specification, reference being had to the accompanying drawings, forming part thereof.

Figure 1 is a side elevation of a lighting fixture arm, showing our new design; and Fig. 2 is a plan view thereof.

We claim:

The ornamental design for a lighting fixture arm, as shown.

HERMAN A. SAFION.
MORIS GERINGER.
